File. 377

Stafford & Co, Troy N.Y. assignees of E. Ripley, Troy, N.Y.
Letters Patent No. 377. Dated May 27, 1851.

The Schedule referred to in these Letters Patent and making part of the same

To all to whom these presents shall come:

Be it known

that I, Ezra Ripley of Troy, in the County of Rensselaer and
State of New York, have invented or produced a new class of

of parlor stove, which I call the Regulator and I do hereby declare the following is a full and exact description of the front and end plates of the same, reference being had to the annexed drawings making a part of this specification in which, fig. 1, is a view of the front plate and fig. 2 of the end plate of the stove.

The style of ornament consists of arabesque figures combined as represented in the drawing.

The ornament is only represented in part, the blank part of the plate having the same ornament as that represented.

What I claim and desire to secure by Letters patent, is the design and configuration of ornamented stone plates substantially the same as described and represented herein.
